UNITED STATES PATENT OFFICE.

JAMES OTIS PERSONS, OF NORFOLK, VIRGINIA.

METHOD OF LINING PIPES.

942,184.

Specification of Letters Patent.

Patented Dec. 7, 1909.

Application filed October 14, 1908. Serial No. 457,761.

To all whom it may concern:

Be it known that I, JAMES O. PERSONS, a citizen of the United States, residing at Norfolk, in the county of Norfolk and State 5 of Virginia, have invented new and useful Improvements in Methods of Lining Pipes, of which the following is a specification.

My invention relates to a method of lining pipes with lead or similar material, and 10 more particularly, to a method for lining either straight or curved pipes after they have been cut, finished, or set in any desired structural relation.

The invention is especially well adapted 15 for lining the various pipe lines found on ship board, but is not, of course, limited to such use, as it lends itself readily to widely varying classes of work.

Broadly considered the invention con- 20 templates the provision of improved means for uniformly expanding a tube of malleable material, such as lead, from one diameter to a greater predetermined diameter, throughout its length.

More specifically, the invention seeks to 25 provide means for producing a lead or similar lining in a given pipe by inserting a lead tube of smaller diameter into said pipe, and then expanding said lead tube until it is 30 forced into close contact with the walls of the outer pipe. It has heretofore been pro- posed to accomplish this result by hydraulic pressure, but it is found in practice, that, 35 where this method is employed, air bubbles are formed between the walls of the two pipes, and hence the intimate contact re- 40 quired can not be obtained. It has also been proposed to line iron or similar pipes with lead, at the time of their manufacture into 45 stock of standard length. This is accom- plished by clamping the straight lengths of 50 pipe in suitable vises, inserting the lead lin- ings, and then expanding them by means of a tool or spreader carried by a mandrel.

This method is obviously applicable only to 45 straight pipe. Furthermore, it has been 55 found that, when such pipe is cut for the purpose of fitting or setting the same, the lining becomes separated from the pipe at the point of cutting, and it is thereafter ex- tremely difficult to cause it to adhere again in a satisfactory manner.

It is, therefore, one object of the present 55 invention to devise a method of lining which shall be applicable to curved, as well as

straight pipe, and to pipe after it has been cut and set into its final position. In this way the necessity of cutting and marring the lining may be obviated.

A further object of the invention is to de- 60 vice a method which shall be equally as well adapted to repair work, *i. e.*, to lining old or corroded pipe, as to new work.

A further object is to devise a method by 65 which air bubbles between the pipe and lin- 70 ing will be eliminated, and a close union of the parts secured.

A still further object of the invention is to 70 provide an improved method of inserting the lead linings into the pipes.

With the above objects in view, the inven- 75 tion consists in the method and apparatus hereinafter described, and illustrated in the accompanying drawings, in which:—

Figure 1 is a view, partly in section, show- 75 ing my improved method of attaching a cab- 80 ble to the tube to be inserted in the pipe. Fig. 2 is a detail end view of such a tube on an enlarged scale. Fig. 3 is a similar view showing the cable in position. Fig. 4 is a 80 side elevation, partly in section, showing the method of inserting a tube into the pipe to be lined. Fig. 5 is a central longitudinal section illustrating the process of expanding the tube within the pipe. Fig. 6 is a similar 85 view showing a carrying forward of the same idea. Fig. 7 is a sectional detail of the end of a finished pipe section, with the lin- 90 ing in place. Fig. 8 is a longitudinal section similar to Fig. 5, but showing a slightly dif- 95 ferent method. Fig. 9 is a central longitudinal section of one form of spreader which I employ. Figs. 10, 11, and 12 are views showing other forms of spreaders adapted to certain classes of work.

Referring to the drawings in detail, 1 des- 100 ignates the malleable tube, which is to form the lining, and which is usually made of lead or similar material, and 2 indicates the pipe to be lined. This pipe may be either iron, copper or other material, and may be either straight or provided with a number of bends.

From experiments heretofore made in in- 105 serting lead tubing into pipes, it has been found that where the pipe is long and crooked it is very difficult to properly insert the tube. It has been found that if tension is applied to the front end of the tube the re- 110 sistance offered to its passage through the

pipe often results in rupturing the tube, and, on the other hand, if it is attempted to push the tube through the pipe by exerting a pressure on its rear end, the tube is apt to 5 buckle and become distorted. To obviate these difficulties I have devised the method shown in Figs. 1 to 4, inclusive. Referring to these figures it will be seen that I form an annular groove 3 near one end of the 10 tube, as by hammering, and a longitudinal groove 4 extends from the annular groove 3, to the end of the pipe. I then place a cable 6 around the tube so that it lies within the groove, and knot it at 7, so that after passing around the tube it may lie in the groove 4, and extend in the direction of the end of the 15 tube. These grooves are simply for the purpose of allowing the cable to lie flush with the outer surface of the tube so as to 20 prevent no obstruction to the passage of the tube through the pipe. The other end of the cable 6 is led back through the inside of the tube and knotted as at 8, a block 9 being interposed between the knot and the end of the 25 tube, as clearly shown in Figs. 1 and 4. It will be understood that the cable 6 is of a length considerably greater than the tube, and that when its ends are attached to the tube, as above described, its middle portion 30 forms a loop. In this loop I place a pulley 10, journaled in the block 11, which block may in turn be attached to a suitable sheaf 12, or other means by which a tractive force may be applied to said block. It will thus 35 be seen that by pulling on the block 11, the tension in the two portions of the cable on opposite sides of the pulley 10 will be equalized, and the result will be the application of an equal force simultaneously to both 40 ends of the tube 1. If desired, and particularly where the tubes are large, I may employ a strap or bail 5 soldered or otherwise secured to the end of the tube, and may tie the cable to this bail before securing it to 45 the tube at 17. This is for the purpose of centralizing the pull on this end of the tube. It will be understood, of course, that the 50 tube is of considerably smaller diameter than the pipe in which it is inserted, and that after the tube has been inserted, it is necessary to expand the same into contact with the inner walls of the pipe. For this purpose I employ a device which I designate a spreader, and various forms of which 55 are illustrated in Figs. 9, 10, 11, and 12. Referring to Fig. 9, which illustrates the type of device employed for straight pipes, 23 designates a cylindrical block, having its front end tapered or cone shape, as indicated at 23'. A bolt 25, having a rounded head 26, passes centrally through the block 23, and is provided at its rear end with a nut 27. Under the nut 27 is a washer 28, and between the washer 28 and the block 60 23 is clamped a cup shaped leather disk, 65

such as is used to form the packing for pump pistons and the like. In Fig. 10, I have illustrated a spreader of the same general shape, but the block 23^a, instead of being cylindrical, is more or less parabolic, 70 and the head of the bolt preferably conforms to the curve of the block, as shown.

Referring now to Figs. 5 and 6 I have illustrated a section of pipe 2, having a tube 1 inserted therein. After this tube has 75 been drawn into the pipe, I insert a spreader 23 into one end of the tube, and then also insert the end of a pipe 14, which is provided with a piston-like packing, so as to cause it to fit the tube fluid tight. As 80 shown, this packing consists of a leather disk 16 clamped between two plates 18 and 20, and held in position by means of nuts 15 and 19. It may be here stated that the end of the tube 1 is flattened out so as to 85 form a flange 1^a, which fills a recess 2^a, in the flange 2^a, of the pipe 2, as clearly shown in Fig. 7. By reference to this figure, it will also be seen that the outer face of the flange 2^a is preferably rounded off, as indicated at 2^c. Consequently when the adjacent ends of two sections of pipe are 90 arranged so that the flanges 1^a abut, and bolts are inserted through the holes 2^b, in the flanges 2^a, a fluid tight joint will be 95 formed between the flanges of the lead lining without the use of any gasket or other packing devices.

Referring again to Figs. 5 and 6, after inserting the pipe 14 in the end of the tube, 100 I slip over it a short piece of pipe 17 to act as a brace, and over this I secure a clamp 21, attached at one side of the flange 2^a by means of a bolt 22. If, therefore, fluid pressure, such as hydraulic pressure, be 105 admitted through pipe 14, it will be seen that the spreader 23 or 23^a will be driven through the tube, and will expand the same into contact with the walls of the pipe, as shown in Fig. 5. It will be particularly 110 noted that owing to the travel of the spreader through the tube it is expanded progressively from one end to the other, and consequently all air bubbles which would 115 tend to collect between the tube and pipe, are smoothed out and eliminated. In order to still further compact the tube, and to 120 secure an even more intimate contact with the pipe, I preferably employ the additional step illustrated in Fig. 6. This consists in providing a clamp 21^a at the exit end of the pipe so disposed that when the spreader 23 reaches this end of the pipe, its movement will be arrested by the clamp. With the parts in this position, hydraulic 125 or other pressure is admitted to the pipe until the pressure very greatly exceeds that employed for driving the spreader through the tube. This results in forcing the malleable tubing into every irregularity on the 130

inner surface of the pipe, and securing a very intimate contact therewith, and at the same time, this operation serves as a pressure test to determine whether or not the finished pipe will stand the pressure for which it is designed; to this end, suitable gages (not shown) are, of course, employed. After this test pressure has been applied, the clamp 21^a is removed, the confined fluid 10 allowed to escape, the tube 1 cut off at the proper length, and its end bent over to form a flange 1^a, as above described.

Although the form of spreader shown in Fig. 10 will ordinarily suffice for curved pipes, it may sometimes be desirable, where the work is particularly complicated, or where the bends in the pipe are sharp, to employ a series of short spreaders operating one behind the other, as shown in Fig. 8. 15 20 With this arrangement, I prefer to make the spreaders of progressively increasing diameter, and the first of the spreaders may be simply a ball, as shown in Fig. 12. The intermediate spreaders may have a conical 25 point and a concave base, as shown in Fig. 11, to receive the point of the next succeeding spreader, while the last spreader of the series is provided with the packing ring 24, so as to secure a fluid tight fit. It will be 30 observed that a series of spreaders used in straight pipes give the same advantages that they give when they are used with curved pipe. These advantages result mainly from an increased flexibility of the spreader by 35 virtue of its being made in sections, thus constituting a series of spreaders, if we consider each section a spreader, and from a decreased friction between the expanding surface and the surface of the tube being expanded on account of the decreased area of 40 the surface of the spreader in contact with the tube. The flexibility resulting from the formation of the spreader in sections enables the pipe to freely pass over the irregularities in the tube being expanded or pipe being expanded, whether that pipe be straight or curved. The decreased friction means an easier and more efficient operation, as well as more accurate and better work, as there is 45 less tendency for the tube being expanded to lag more at one side than another, and thus cause thin spots in the wall of the tube, or for the friction to become so great that the tube being expanded is drawn at a point 50 adjacent the rear end of the spreader and the walls thinned. This thinning of the walls of the tube may result in a breaking of the tube in case the friction becomes too great. A further advantage of the use of 55 a series of spreaders is the fact that when the lining tube is of a diameter so much smaller than the tube to be lined that the expansion is too great to be performed by a single spreader, by the use of a series of 60 spreaders of progressively increasing diameter, 65

the tube may be expanded at once into place as a lining. If single spreaders were used, three separate operations would be necessary in order to attain this result.

I do not in this application claim the apparatus for carrying out my method. This forms the subject of a divisional application.

It will thus be seen that I have devised an improved method both of inserting the tube into the pipe to be lined, and also of expanding the same, so as to eliminate air bubbles and to secure the most perfect contact possible, and it is thought that the numerous advantages of my invention will be readily appreciated by those skilled in the art.

What I claim is:—

1. The method herein described of expanding a malleable tube which consists in simultaneously forcing a series of spreaders of progressively increasing diameter through 85 said tube.

2. The method herein described, of expanding a malleable tube which consists in simultaneously forcing a series of spreaders of progressively increasing diameter through 90 said tube, the said spreaders having expanding surfaces of less length than the overall length of the spreader, whereby the friction between the spreaders and the tube is decreased.

3. The herein described method of lining pipes which consists in first, inserting into the pipe to be lined a malleable tube of less diameter; secondly, expanding said tube progressively from end to end; and thirdly, 100 forcing said tube into intimate contact with the pipe by means of fluid pressure.

4. The herein described method of lining pipes which consists in inserting into the pipe to be lined a malleable tube and expanding said tube progressively by driving a spreader therethrough by means of fluid pressure acting directly against said spreader, whereby all air between the tube and pipe is 105 expelled.

5. The herein described method of lining pipes which consists in; first, drawing into the pipe to be lined a malleable tube of less diameter; second, inserting into one end of said tube a suitable spreader; third, admitting fluid pressure behind said spreader so as to drive the same through said tube; and fourth, arresting the movement of said spreader at the other end of said tube and increasing the fluid pressure within the tube. 115

6. The method of lining pipe which consists in first inserting the lining in the form of a tube, then entering a suitable spreader at one end of the tube, and then driving said spreader from one end of the tube to the 125 other by applying fluid pressure behind it.

7. A method of lining curved pipe which consists in first inserting into the pipe a tube of lining material, second, inserting into one end of said tube a series of spreaders of pro- 130

gressively increasing diameter, and third, forcing said spreaders through the tube by applying fluid pressure behind them.

8. The method of lining pipe which consists in first inserting the lining in the form of a tube, and then forcing through said tube a series of spreaders of progressively increasing diameter and in contact one with another, whereby the lining tube is expanded into place by stages in a single operation, and whereby the spreaders pass freely irregularities in the lining and in the pipe being lined.

9. The method of lining pipe which consists in inserting first the lining in the form of a tube of less diameter than the pipe, and then forcing through said tube by fluid pressure a series of spreaders of progressively increasing diameter in contact one with another and having curved expanding surfaces

spaced apart, whereby the spreaders pass freely irregularities in the lining and in the pipe being lined.

10. A method of lining pipe which consists in first inserting the lining in the form of a tube of lining material, second inserting a series of short spreaders having curved expanding surfaces of progressively increasing diameter, and third stopping up the end of the tube behind the spreaders, and fourth applying fluid pressure behind the spreaders to force them through the tube.

In testimony whereof I have hereunto set my hand in presence of two subscribing witnesses.

JAMES OTIS PERSONS.
